SYDNEY ASHDOWN, OF VANCOUVER, BRITISH COLUMBIA, CANADA.

ELECTRICAL-LAMP WIRE CONNECTION.

979,636.

Specification of Letters Patent. Patented Dec. 27, 1910.

Application filed January 11, 1910. Serial No. 537,434.

To all whom it may concern:

Be it known that I, SYDNEY ASHDOWN, a citizen of the Dominion of Canada, residing at Vancouver, in the Province of British Columbia, Canada, have invented a new and useful Electrical-Lamp Wire Connection, of which the following is a specification.

This invention relates to a device whereby several incandescent lamps may be rapidly connected to one pendant cord from a wall or ceiling rosette.

Where pendant cords are used objection is urged to the attachment of more than one cord to one rosette owing to the difficulty of making a satisfactory connection of more than one wire to the binding screws of the rosette. It is to overcome this difficulty and to provide a simple and inexpensive attachment of a branch cord or cords that the device which is the subject of this application has been devised.

The invention is particularly described in the following specification, reference being made to the drawings by which it is accompanied, in which:

Figure 1 is a longitudinal section of the invention showing it in its simplest form, Fig. 2, a side elevation of a modified form showing an external guide and support for each push pin, Fig. 3, an edge elevation of the same with the push pin removed, and Fig. 4, a cross section on the line A A in Fig. 2.

In these drawings the main pendant wires, positive and negative, are respectively represented by 2 and 3, each being composed, as is usual, of multiple strands of fine wire, and 4 the socket of the lamp which they serve. These wires 2 and 3 are separated at the desired location for the branch connection, and in the opening between them is inserted an ovoid body 5 of insulating material the edges of which are deeply grooved as at 6 for the reception of the separated wires 2 and 3. The body 5 is also notched inward from its edges as at 7 and 8, each notch terminating in a seat for the reception of the separated wires 9 and 10 of the branch connection which it is desired to attach to the main pendant; to one or both ends of which branch, lamp sockets 11 and 12 are attached.

Metallic push pins 15 having caps or heads 16 of insulating material are inserted through the wires 2 and 3 where they lie in the grooves 6 and are pressed through aper-

tures provided for them in the body 5 and through the wires 9 and 10 of the branch as they lie in the notches 7 and 8, so that an electrical connection is made between 60 the positive wire 3 of the main pendant and the positive wire 10 of the branch, and on the other side the other push pin connects the negative wire 2 of the main pendant with the negative wire 9 of the branch. The 65 current passing through the wires 2 and 3 of the main pendant is thus divided at the branch connection and will pass also through the branch circuit 9 and 10 to each lamp 11 and 12 of the branch. This is the 70 essential feature of the invention in its simplest form: the provision of a means whereby a branch or branches may be connected to the circuit of a pendant lamp.

The branch lamps can at any time be 75 readily disconnected by withdrawing one of the push pins 15 far enough out to clear it from contact with the strand wires of the branch circuit without withdrawing it altogether, and can as readily be restored, as 80 the resiliency of the insulating wrapping of the wire has sufficient grip on the pin to retain it in place when so withdrawn.

The sharp pointed metal push pins 15 being pressed through the multiple strands of 85 the wires 2 and 9, and 3 and 10 while they are still bound together by their insulating wrapping will form a sufficient metallic contact with them to insure an efficient electrical connection and connect the circuit of the 90 branch into the circuit of the main pendant.

To insure that the push pins 15 will be guided direct through the center of the main pendant wires 2 and 3 which lie in the groove 6, these pins 15 are provided, as shown in 95 Figs. 2, 3 and 4, outside of the groove 6 with a bearing in a small boss 17 projected on each side from one face of the ovoid body 5, so as to leave the other side clear for the insertion of the separated wires 2 and 3 and 100 adjacent to the seats at the bottom of the notches 7 and 8 in which the wires 9 and 10 lie, bosses 18 may be formed on the sides of 5 so that the wires 9 and 10 are not too sharply bent over the edges of the notch 105 seats.

It will be obvious that although the device is shown as for a single branch carrying two lights, there is no reason why a number of similar branches may not be connected in 110 one branch connecting body 5.

Having now particularly described my in-

vention and the manner of its application, I hereby declare that what I claim as new and desire to be protected in by Letters Patent, is:

- 5 1. A device for the purposes specified comprising a body insertible between a pair of insulated main line wires to separate the same, said body having provisions for receiving a pair of branch line wires intermediate the ends thereof to separate said branch line wires from one another and from said main line wires, and means passing through corresponding main and branch line wires and the insulation thereof for electrically connecting corresponding main and branch line wires without destroying the insulating covering of said wires.
- 10 2. As a device for the purpose specified, means for separating the positive and negative wires of a pendant lamp circuit intermediate the ends thereof, means adjacent thereto for separating intermediate their ends the wires of the branch which it is desired to connect, and means for electrically connecting through suitable insulation a separated wire of each circuit without impairing the continuity of either circuit.
- 15 3. A device for the purpose specified, comprising a body of ovoid form grooved around its edges to receive the separated positive and negative wires of an electric circuit and notched from the outside edge toward the center to receive the separated positive and negative wires of another circuit, insulation between the several adjacent wires, and metallic pins one of which is pushed through the positive wires of the two circuits and the other through the negative wires of the two

circuits so as to electrically connect one circuit with the other.

4. A device for the purpose specified, comprising an ovoid body of insulating material said ovoid body having its edges deeply grooved to receive the separated wires of a lamp circuit and having notches through its thickness from the edges toward the center of it for the reception of the separated wires of a branch circuit which it is desired to connect to the other circuit, and sharp metal pins having heads of insulating material said pins connecting the positive wire of one circuit to the positive wire of the other and on the other side connecting the negative wire of one circuit to the negative wire of the other.

5. A device for the purpose specified, comprising an ovoid body of insulating material deeply grooved around its edge to receive the separated positive and negative wires of an electric circuit and notched from its outer edge toward the center to receive the separated positive and negative wires of another circuit, a metal pin slidable in the insulating body and through the separated positive wires, a similar pin through the separated negative wires, and means for slidably supporting these pins exterior to the wire in the groove.

In testimony whereof I have signed my name to this specification in the presence of two subscribing witnesses.

SYDNEY ASHDOWN.
